DESIGN FOR A PROTRACTOR

Kenneth P. Kidd, Gainesville, Fla.

Application August 24, 1940, Serial No. 94,604

Term of patent 14 years

To all whom it may concern:

Be it known that I, Kenneth P. Kidd, a citizen of the United States, residing at Gainesville, in the county of Alachua and State of Florida, have invented a new, original, and ornamental Design for Protractors, of which the following is a specification, reference being had to the accompanying drawing, forming part thereof.

The figure is a plan view of a protractor, showing my new design.

I claim:

The ornamental design for a protractor, as shown.

KENNETH P. KIDD.
